UNITED STATES PATENT OFFICE.

ALBERT R. PADDOCK, OF FARMDALE, OHIO.

CONCRETE PAVEMENT.

1,231,419.

Specification of Letters Patent. Patented June 26, 1917.

Application filed November 28, 1916. Serial No. 133,965.

To all whom it may concern:

Be it known that I, ALBERT R. PADDOCK, a citizen of the United States, residing at Farmdale, in the county of Trumbull and State of Ohio, have invented new and useful Improvements in Concrete Pavements, of which the following is a specification.

The present invention relates to concrete pavements, and it proposes, briefly, a pavement of that general character which constitutes, in effect, a continuous concrete slab provided with expansion joints placed accurately and at short, regular intervals, both longitudinally and transversely throughout the slab, so as to completely avoid the most common defect in concrete pavements as ordinarily constructed,—*i. e.*, a slight upheaval, and, at times, a positive break in the surface of the pavement at the transverse expansion joints, due to uneven or excessive expansion.

According to the invention, concrete paving blocks, in the form of rims or shells, are laid out in rows and supported at their corners upon surfacing blocks, whose upper and lower faces are covered with mortar, the surfacing blocks resting, in turn, upon the bed course. The paving blocks are bound along their marginal faces with strips of water-proof material which form the joints above referred to, and which yield to compensate for expansion and contraction. In laying out the rows of paving blocks, the latter are spaced apart at intervals equal to the width of the blocks, the arrangement of each succeeding row being the reverse of the preceding row, so that when all of the blocks have been positioned in this way, the whole will present a checkered or criss-cross appearance; and since the paving blocks rest upon the surfacing blocks, they will be supported above the bed course, thereby providing spaces which communicate both with the open central portions of the paving blocks, and with the open spaces between adjacent blocks. It follows, therefore, that when these spaces are completely filled with plastic concrete, and the latter has set, the resultant structure will virtually form a single homogeneous body wherein the pav-

ing blocks are firmly anchored, the dimensions of such body corresponding to those of the area to be paved.

Referring to the accompanying drawing, wherein an embodiment of the invention is illustrated:

Figure 1 is a plan view of a portion of the improved pavement.

Figs. 2 and 3 are transverse sections on the lines 2—2 and 3—3, Fig. 1, respectively, Fig. 3 being on an enlarged scale.

Fig. 4 is an enlarged edge view, partly in section, taken from the left-hand side of Fig. 1.

Fig. 5 is an enlarged longitudinal section on line 5—5, Fig. 1.

Fig. 6 is a perspective view of one of the improved paving blocks.

Fig. 7 is a fragmental plan view, on a reduced scale, showing the arrangement of the blocks in constructing a curve in the pavement.

As shown in said drawing, the paving blocks used, are of skeleton construction. The block represented in Fig. 6 may be taken as illustrating the general shape preferred, though such shape, is, of course, susceptible of modification, as well as the dimensions of the block. In any case, however, whatever may be the precise marginal outline of the block, the latter comprises merely a skeleton, or rim-like body or shell 10, as aforesaid, which is constructed of solid concrete, suitably reinforced internally, the entire central portion 11 of the block being open. The reinforcements for the block are preferably constituted by flat wire bands 12 and 13, which are disposed longitudinally of the side and end members respectively of the blocks, and are bent to form, substantially, two elongated triangles, arranged apex to apex, the adjacent end portions of the bands intersecting each other, and being extended beyond their points of intersection, as clearly shown in Figs. 3, 5 and 6. At their central portions,—that is to say, at the meeting points of the apex portions of the triangular members of the bands,—the said bands are intersected by relatively-small triangular members 14 and 15 likewise formed by wire 100

bands, these members being disposed transversely of the side and end members of the blocks and having their free ends extending across the strands of the corresponding main bands 12 and 13 above and below the same.

5 Each paving block is provided along its entire marginal face with a strip of yielding material 16, preferably tarred felt or paper, constituting the expansion joint above referred to. These strips are held in place by the butt ends of the various bands 12, 13, 14 and 15, which project through the marginal faces of the block and take over said strips, so that the said bands function not only as 10 reinforcements for the blocks, but also as fasteners for the strips, as will be apparent.

15 The paving blocks, as previously stated, are supported at their corners upon surfacing blocks, indicated at 17. These surfacing blocks are constructed of concrete, or other 20 suitable material, and have coats of mortar 18 applied to their opposite faces, so as to form joints between the paving and surfacing blocks, and between the latter and the 25 bed course 19, said bed course being thoroughly compacted and trued to section, line and grade previous to the laying of the surfacing blocks. The paving blocks are laid 30 in the mortar on the upper faces of the surfacing blocks, and are themselves trued to the line and grade of the surface of the finished road, street or side walk, as the case 35 may be, it being understood, of course, that the invention contemplates the application of the improved pavement alike to any of these classes of highway, as well as to others of an analogous character. However, the pavement is primarily designed for application 40 to roadways, and has been so illustrated.

45 In constructing the pavement, the spacing blocks are first laid in the proper manner upon the previously compacted and trued bed course from berm to berm, and are held in place by the mortar on their lower faces. The paving blocks are then 50 laid out, row by row, the blocks in each row alternating with open spaces 20 of the same width as the blocks themselves, and the arrangement of blocks and spaces of each succeeding row being the reverse of that of the preceding row, so that when all of the rows 55 have been laid out, the work will resemble a checker-board in its general appearance. The blocks of each row rest at their corners 60 in the mortar on the upper faces of the surfacing blocks, and, in the case of the blocks at the ends of the rows, additional surfacing blocks are used which support the entire outer side edges thereof, as shown in Figs. 1 and 4. The ends of the paving blocks project 65 a short distance into the open spaces 20 of the rows next in front and in rear thereof; and, in laying out a straight stretch of road, the extent of such projection or overlapping

is the same for all of the blocks of a row. 65 In laying out a curve, however, the extent of projection varies according to the degree of curvature; and, in the case of the blocks of a row, gradually decreases from the inner berm line to the outer berm line, as will be 70 apparent upon inspection of Fig. 7.

75 Where open spaces occur at the ends of the rows, wooden planks 21, or the like, are employed to close the outer sides of such openings, and are held in place by means of suitable stakes 22, these planks being sufficiently long to completely span the openings and project at their ends across the outer side faces of the adjacent paving blocks. 80

85 The mounting of the paving blocks upon the surfacing blocks, has the effect of supporting the former above the bed course, so that spaces will be produced between the bottoms of the blocks and the bed course which communicate with one another and, also, with the openings or spaces 11 and 20, as well. Consequently, when the laying out 90 of the rows has been completed and all of the openings have been entirely filled with concrete 23, the latter will pass through the various spaces and will form one large homogeneous body or slab, whose linear dimensions are those of the area to be paved, and whose thickness equals the combined 95 thickness of the surfacing and paving blocks and the two mortar joints, the said surfacing and paving blocks being firmly anchored therein.

100 The construction of a pavement in the manner above described, has the advantage of permitting not only careful inspection and testing of all of the paving blocks, but also of the crown, surfacing and alinement of the roadway, before the concrete filler is 105 poured. Defective concrete filling may readily be detected upon final inspection, and, when discovered, can easily be dug out and replaced by proper material, since it will be found in distinctly-marked units of 110 space,—i. e., in the centers of and between the blocks. On the other hand, no test of the concrete is possible, under the method of construction ordinarily in use, until it has firmly set, a period of from three to ten 115 days, when defective concrete may be found spread over wide irregular areas, very difficult to remove and to replace. Furthermore, the use of forms is avoided with the present system, thus overcoming the danger of 120 irregularities in the alinement, crown and surfacing of the road—which cannot be repaired after the concrete has set—produced by accidental displacement of the forms during pouring. The omission of forms, and of 125 the templets used in connection therewith, also conduces to increased accuracy in the finished pavement, since any irregularity in

the side forms, which constitute the tracks for the templet, produces an irregularity in the surface of the roadway; while the coarse aggregate is often worked to the top by the 5 templet, and causes a rough, unsightly surface, very difficult to remedy. Finally, it will be apparent that where the pavement is to be constructed for light or medium traffic, a poorer mix of concrete may be used to 10 within two inches of the surface, and a richer mix from this point to the surface, thus greatly reducing the cost of construction.

I claim as my invention:

15 1. A pavement in the form of a single continuous concrete slab whose lineal dimensions equal those of the area to be paved; said slab comprising rows of concrete paving blocks, the individuals of 20 which are spaced apart at regular intervals, the arrangement of alternating blocks and spaces in each succeeding row being the reverse of that in the preceding row, surfacing blocks supporting said paving blocks 25 above the surface of the road bed, so as to provide open spaces between the paving blocks and the road bed which communicate with one another and with the spaces between adjacent blocks, and a concrete filler 30 completely occupying all of said open spaces and anchoring the paving blocks and surfacing blocks in place therein.

2. A pavement in the form of a single continuous concrete slab whose lineal dimensions equal those of the area to be paved; 35 said slab comprising rows of concrete paving blocks, having open central portions, said paving blocks individually spaced apart at regular intervals, the arrangement of 40 alternating blocks and spaces in each succeeding row being the reverse of that in the preceding row, surfacing blocks supporting said paving blocks above the surface of the road bed, so as to provide open spaces 45 between the paving blocks and the road bed which communicate with one another, with the open portions of said blocks and with the open spaces between adjacent blocks, and a concrete filler completely occupying 50 all of said open spaces and anchoring the paving blocks and surfacing blocks in place therein.

3. A pavement in the form of a single continuous concrete slab whose lineal dimensions equal those of the area to be paved; 55 said slab comprising rows of concrete paving blocks, the individuals of which are spaced apart at regular intervals, the arrangement of alternating blocks and 60 spaces in each succeeding row being the reverse of that in the preceding row, surfacing blocks supporting said paving blocks above the surface of the road bed, so as to provide open spaces between the paving

blocks and the road bed which communicate 65 with one another and with the spaces between adjacent blocks, and a concrete filler occupying all of said open spaces and anchoring the paving blocks and surfacing blocks in place therein; each paving block 70 having a strip of yielding, waterproofed material bound around its entire marginal surface, so as to form expansion joints placed accurately and at regular intervals, both longitudinally and transversely 75 throughout the slab.

4. A pavement in the form of a single continuous concrete slab whose lineal dimensions equal those of the area to be paved; 80 said slab comprising rows of concrete paving blocks, having open central portions, said paving blocks individually spaced apart at regular intervals, the arrangement of alternating blocks and spaces in each succeeding row being the reverse of that in the preceding row, surfacing blocks supporting 85 said paving blocks above the surface of the road bed, so as to provide open spaces between the paving blocks and the road bed which communicate with one another, with 90 the open portions of said blocks and with the open spaces between adjacent blocks, and a concrete filler completely occupying all of said open spaces and anchoring the paving blocks and surfacing blocks in place 95 therein; each paving block having a strip of yielding, waterproofed material bound around its entire marginal surface, so as to form expansion joints placed accurately and at regular intervals, both longitudinally and 100 transversely throughout the slab.

5. A pavement in the form of a single continuous concrete slab whose lineal dimensions equal those of the area to be paved; said slab comprising rows of concrete paving blocks, the individuals of which are spaced apart at regular intervals, the arrangement of alternating blocks and spaces in each succeeding row being the reverse of that in the preceding row, surfacing blocks supporting said paving blocks above the surface of the road bed, so as to provide open spaces between the paving blocks and the road bed which communicate 105 with one another and with the spaces between adjacent blocks, and a concrete filler completely occupying all of said open spaces and anchoring the paving blocks and surfacing blocks in place 110 therein; each paving block having a strip of yielding, tarred material bound around its entire marginal surface, so as to form expansion joints placed accurately and at regular intervals, both longitudinally and transversely throughout 115 the slab.

6. A skeleton paving block, comprising a shell or rim of solid concrete having internal reinforcing devices embedded therein 120

and projecting through the outer marginal surface thereof, and a continuous strip of yielding, waterproof material bound entirely around said outer marginal surface and retained in place by the projecting portions of said reinforcing devices.

In testimony whereof I have hereunto set

Copies of this patent may be obtained for five cents each, by addressing the "Commissioner of Patents, Washington, D. C."

my hand in presence of two subscribing witnesses.
